UNITED STATES PATENT OFFICE

2,143,637

REFRIGERATING SYSTEM

Carl W. Vollmann, Montreal, Quebec, Canada

Application May 12, 1937, Serial No. 142,216

2 Claims. (Cl. 286—19)

This invention relates to compressors for refrigerating machines and particularly to improved means for cooling the piston rod and preventing overheating and destruction of the piston rod

5 packing.

According to this invention the stuffing box is provided with spaced inner and outer chambers surrounding the piston rod passing therethrough, each chamber being located between sections of 10 packing material. The outer chamber is suitably supplied with lubricating oil to provide an oil seal and to ensure adequate lubrication of the piston rod. The inner chamber is connected to the high pressure side of the refrigerating system 15 so that, through the manipulation of a suitable valve, a small amount of the liquid refrigerant may be supplied to said chamber and brought into direct cooling contact with the outer surface of the piston rod. The inner chamber serves as a 20 small expansion chamber in which the expansion of the liquid refrigerant in direct contact with the surface of the piston rod has a very substantial cooling effect and prevents overheating and destruction of the packing.

25 Another advantage resulting from this method of cooling the piston rod is that the oil supplied to the outer chamber retains its lubricating qualities for a longer period and is more effective in reducing friction and prolonging the life of 30 the piston rod and packing.

In the preferred embodiment of this invention the liquid refrigerant employed for cooling the piston rod is supplied to the inner chamber of the stuffing box through a valve controlled pipe leading 35 from the high pressure side of the refrigerating system, said pipe being preferably connected to the line leading from the liquid receiver to the refrigerating or expansion coil of the refrigerant circulating system. The liquid refrigerant, on 40 entering the inner chamber of the stuffing box, vaporizes or expands in direct cooling contact with the surface of the piston rod and is then withdrawn from said chamber through a suction pipe connected to the low pressure side of the 45 refrigerating system. This last mentioned pipe may be connected to the suction line of the refrigerating system (in the case of single stage compression) or it may be connected to the intermediate pressure line where multi-stage 50 compression is employed.

Proceeding now to a more detailed description reference will be had to the accompanying drawing, in which—

Figure 1 is a view partly in side elevation and 55 partly in vertical section of a horizontal com-

pressor equipped with a stuffing box designed in accordance with this invention.

Figure 2 is an enlarged vertical sectional view of the stuffing box.

Figure 3 is a view similar to Fig. 1 but showing 5 the application of the invention to a vertical compressor.

In the construction shown in Figs. 1 and 2, 5 designates the cylinder of a double acting compressor provided with a stuffing box 6 through 10 which the piston rod 7 passes. The inner and outer chambers provided in accordance with this invention are respectively indicated at 8 and 9. The chamber 8 is located inwardly of the chamber 9 and presents inner and outer channels 15 formed by the sides of an H-shaped metal ring 10 interposed between the packing rings 11 and the intermediate packing rings 12, the two channels being in communication with each other through connecting passages 10a formed in the 20 web portion of the metal ring. Liquid refrigerant is supplied to the inlet 13 of chamber 8 through a supply pipe 15 equipped with a valve 16. Pipe 15 is connected to the high pressure side of the refrigerating system at any suitable point between 25 the liquid receiver and the expansion coil of said system. Pipe 16, may, for example, be a branch connection from the line 17 through which the liquid refrigerant is passed from the liquid receiver to the refrigerant coil of the system. The 30 valve 16 enables the supply of liquid refrigerant through the pipe 15 to be regulated in accordance with requirements.

As the liquid refrigerant enters chamber 8 through the inlet 13 it is sprayed inwardly 35 through the passages 10a and expands in direct cooling contact with the outer surface of the piston rod 7. The refrigerant is then conducted from chamber 8 to the low pressure or suction side 18 of the refrigerating system through the 40 pipe line 19.

The oil sealing chamber 9 also presents inner and outer annular channels formed between the sides of an H-shaped metal ring 21 interposed between the intermediate packing rings 12 and 45 the outer packing rings 22, said channels communicating with each other through suitable opening 21a formed in the web portion of ring 21. The channels and communicating passages of the oil chamber 9 are maintained filled with 50 oil under a pressure greater than the suction pressure of the compressor. The oil is supplied to chamber 9 through a pipe 24 leading from the bottom of an oil reservoir 25 in which the oil level is maintained at a suitable height to give 55

the requisite pressure in chamber 9. The oil may be supplied to the reservoir 25 through a top filling opening closed by the removable cover 26 or it may be pumped into the reservoir through a supply line 27 which connects with the pipe 24 as indicated at 28. The space in the oil reservoir above the oil level is connected to the suction line 18 of the compressor by the pipe connections 29 and 19 so that the oil supplied to the oil sealing chamber 9 is maintained under a pressure which varies according to the suction pressure of the compressor but is always higher than the suction pressure, it being understood that pressure in the oil chamber 9 is equal to the suction pressure of the compressor plus the head pressure of the oil in the standpipe 24 and the reservoir 25.

Since the oil pressure in chamber 9 is always higher than the suction pressure of the compressor it is manifestly impossible for the gaseous refrigerant to leak past this chamber.

The pipe lines 24, 27 and 29 are provided with suitable shut off valves indicated at 31, 32 and 33.

Fig. 3 shows the application of the same invention to a vertical type compressor. While this figure does not show the pipes 15, 19 and 24 connected as in Fig. 1, it will be understood that this would be the case in actual practice.

In some cases the reservoir 25 and the pipe connection 29 are omitted and the oil is delivered directly to the chamber 9 and maintained at a suitable pressure.

Having thus described my invention, what I claim is:—

1. In a refrigerating system, the combination with the cylinder and piston rod of a reciprocating compressor, of a stuffing box provided with inner and outer non-communicating chambers surrounding the portion of the piston rod passing through the stuffing box, each of said chambers

being located between sections of packing material surrounding the piston rod, means for maintaining the outer chamber filled with lubricating oil under a pressure higher than the suction pressure of the compressor, means for conducting liquid refrigerant from the high pressure side of the refrigerating system directly to the interior of said inner chamber so that the liquid refrigerant expands in said chamber in direct cooling contact with the piston rod and a return connection through which the expanded refrigerant is immediately passed from said inner chamber back to the low pressure side of the refrigerating system, said return connection being at all times in open communication with said expansion chamber.

2. In a refrigerating system, the combination with the cylinder and piston rod of a reciprocating compressor, of a stuffing box provided with inner and outer non-communicating chambers surrounding the portion of the piston rod passing through the stuffing box, each of said chambers being located between sections of packing material surrounding the piston rod, an oil reservoir mounted above the stuffing box, an oil pipe leading from the bottom of the reservoir to the outer chamber of the stuffing box, a liquid refrigerant supply pipe affording a direct connection between the high pressure side of the refrigerant circulating system and the interior of the inner chamber of the stuffing box, a refrigerant return pipe connecting said inner chamber of the stuffing box to the low pressure side of the refrigerant circulating system, said refrigerant return pipe being always in open communication with said inner chamber and a valve pipe connection between the upper end of the oil reservoir and said refrigerant return connection.

CARL W. VOLLMANN.
